UNITED STATES PATENT OFFICE.

HERMANN JOST, OF BERLIN-TEMPELHOF, GERMANY, ASSIGNOR TO THE FIRM OF "ENUMEHAV," ELEKTRISCHE NIET- UND MEISSEL-HAMMER VERWERTUNGS- GESELLSCHAFT MIT BESCHRÄNKTER HAFTUNG, OF DÜSSELDORF-ÖBERKASSEL, GERMANY.

MECHANICAL HAMMER.

1,123,547

Specification of Letters Patent.

Patented Jan. 5, 1915.

Application filed February 21, 1914. Serial No. 520,143.

To all whom it may concern:

Be it known that I, HERMANN JOST, consulting engineer, a subject of the Emperor of Germany, and a resident of Berlin-Tempelhof, Germany, have invented certain new and useful Improvements in Mechanical Hammers, of which the following is a statement.

The mechanical hammer forming the subject matter of the present invention is intended for riveting hot rivets, for chiseling and all other kinds of work, which were hitherto performed with the aid of pneumatic tools. With all such known hammers the ram is positively withdrawn by the crank gear employed for driving the hammer.

According to the present invention such positive withdrawal is dispensed with. Therefore there will be no backward shock, and the plunger which is rigidly coupled to the connecting-rod will slide back in a smooth manner. The motor may rise to about $\frac{1}{4}$ of its revolution and will yield its entire energy only at the moment of the impact with the spring rigidly connected to the ram. The ram is pushed back by the oscillating spring and by the reaction of the impact on the shank of the chisel at a slower speed than a positively withdrawn plunger, so that, as it has been proved by experiments, the plunger will have already started its forward stroke while the ram during its return stroke has but very little passed the same linear length of its stroke.

The essential requirement for a practical mechanical hammer is that it is avoided that at any point non-elastic blows are produced, as the moment produced by the sudden acceleration of a mass from the condition of inertia must, on the one hand, necessarily lead to the destruction of the one or the other impacting member of the hammer, on the other hand also cause a reaction or rebound, which is very disagreeable to the operator, and which may be considerably reduced by the provision of suitable springs.

In the accompanying drawing: Figure 1 is a longitudinal section of a mechanical hammer embodying my invention, showing the plunger raised; Fig. 2 is a similar section taken at right angles to Fig. 1, and showing the plunger lowered.

The hammer comprises a steel sleeve *a* 55 into the rear end of which the crank casting *b* containing the crank *i* is screwed. In front the sleeve carries the screwed head *c*, into which the chisel, riveting hammer or the like is fitted. The crank, which is preferably counterbalanced, is driven by means of a flexible shaft which is coupled to a high-speed motor. A connecting rod *h* driven by this crank is coupled at its other end with the plunger *g*, so that, when the crank revolves, this plunger is reciprocated in the sleeve and transmits its energy to the ram *d* to which the coiled spring *e* is secured. This spring, which must be made of a suitable size, is rigidly attached to the ram *d*.

The operation of the mechanical hammer is as follows: By a pressure on a knob *k*, the flexible shaft is caused to be rotated (by means not shown) so that crank *i* is 75 revolved. This revolution is then transmitted by the hereinbefore described parts to the plunger *g*. When in its foremost position the plunger presses against the spring *e* attached to the ram, which again 80 bears against the chisel or riveting hammer. The spring *e* is thereby compressed to a certain degree. When the plunger recedes, the spring will rebound, so that the ram receives a vibrating movement. At the following advance of the plunger, the latter will strike the spring at a somewhat earlier moment and the impact will be more violent, whereupon the ram, under action of the mass of the suddenly released spring 85 and assisted by the rebound produced by its impact against the tool jumps higher than before. This vibratory, jumping movement increases rapidly and within a few seconds it will fill up the whole clear space. 90 The spring receives over and again fresh violent blows and absorbs the whole circumferential velocity of the crank, which, transmitted to the ram, imparts to the latter a hammering motion. The whole energy of the motor is therefore combined in the working blow, so that the power consumed is utilized to more than 85%.

I claim:

A mechanical hammer comprising a 105 crank, a cylinder, an inclosed plunger positively and rectilinearly driven by said crank, a ram acting on the tool, a coiled

spring rigidly attached to said ram, said spring being adapted to receive the impact of the plunger at the moment of the maximum linear velocity of the latter, said ram and spring being independent of the plunger and adapted to oscillate between the said plunger and the end of the tool.

In testimony whereof I have hereunto set my signature in the presence of two subscribing witnesses.

HERMANN JOST.
